DANIEL F. PACKER, OF MYSTIC RIVER, CONNECTICUT.

Design No. 3,395, dated March 2, 1869.

DESIGN FOR A TRADE-MARK.

The Schedule referred to in these Letters Patent and making part of the same.

To all whom it may concern:

Be it known that I, DANIEL F. PACKER, of Mystic River, in the county of New London, and State of Connecticut, have originated a new Design for a Trade-Mark, of which the following is a full, clear, and exact description, reference being had to the accompanying drawing, making a part of this specification.

The design consists of a group of flags, "displayed," among which are conspicuous the flags of the United States and Great Britain upon the right hand, and France and Germany upon the left hand, and other flags behind these. In the midst of the group of flags is a figure of Fame, with rays of the rising sun in the background.

The above-described design is surmounted by the words "Silver-Mountain Soap," and in front of crossed

staves of the above-mentioned flags is a shield bearing a representation of the "silver mountain," and the words "Trade-Mark."

The above-described design for a trade-mark, I propose to paint, print, or otherwise delineate upon paper, cloth, wood, or other material, or on the box or package containing my soap, and either plain or in colors.

Having described my design,

What I claim as new, is—

The design for a trade-mark, herein shown and described.

DAN'L F. PACKER.
